Patented February 9, 1904.

UNITED STATES PATENT OFFICE.

JOHN H. PETROSKEY, OF DETROIT, MICHIGAN.

DESIGN FOR A RACK FOR UMBRELLAS AND CANES.

SPECIFICATION forming part of Design No. 36,787, dated February 9, 1904.

Application filed January 18, 1904. Serial No. 189,637. Term of patent 7 years.

To all whom it may concern:

Be it known that I, JOHN H. PETROSKEY, a citizen of the United States, residing at Detroit, in the county of Wayne and State of Michigan, have invented a new, original, and ornamental Design for a Rack for Umbrellas and Canes, of which the following is a specification, reference therein being had to the accompanying drawing, in which the figure is a perspective view of the rack.

What I claim as my invention is—
The ornamental design for rack for umbrellas and canes, as shown.

In testimony whereof I affix my signature in presence of two witnesses.

JOHN H. PETROSKEY.

Witnesses:

JAS. P. BARRY,
EMMA I. BARNES.
